UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,235,705.

Specification of Letters Patent.

Patented Aug. 7, 1917.

Application filed January 14, 1916. Serial No. 72,149.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone exchanges, and more particularly to 10 interoffice trunking systems for telephone exchanges. Its object is to provide for the proper performance of telephonic and various signaling and switch-operating functions.

According to the main feature of this invention, a disconnect signal associated with one office is maintained continuously actuated upon the restoration of a switch employed in the extension of a connection in 20 the other office, means being provided for interruptedly actuating said signal if a switch, employed in the establishment of the connection in the first office, is restored prior 25 to the restoration of the switch in the other office. By this arrangement an operator, noticing the flashing of the signal, will know that she has prematurely taken down the connection and will thus be enabled to 30 establish the connection.

The drawing represents the circuit arrangement of a semi-mechanical system embodying the present invention. The complete equipment and circuits of telephone exchanges necessary for the establishment of connections selectively between various subscribers' lines, not being necessary to a full understanding of the invention, are not shown in the drawing. There are numerous well-known mechanisms for this 35 purpose. It is sufficient to assume that connections may be established through several line and trunk switches, the exact number and kind of which may be varied without departure from the invention.

Two subscribers' stations 1 and 2 are shown, which may be connected under the control of a connecting operator by way of a spring-jack 3 and a plug switch 4, contacts 5, 6 of an automatic switch, two wires 7, 8 of a two-wire interoffice trunk, and under the control of another operator through a plug switch 9 and a spring-jack 10. The connecting link between jack 3 and contacts 5,

6 may be divided as usual by a repeating 55 coil 11 into inductive sections, and the trunk likewise by a repeating coil 12.

The subscriber at substation 1, desiring to initiate a call, removes his receiver from the switchhook, causing thereby the energization of a line relay 13 in the well-known manner, which line relay then operates a calling line signal 14. The connecting operator inserts her plug 4 into jack 3 in which the calling subscriber's line terminates, 65 establishing thus a circuit from ground through the winding of a relay 15, the sleeve contacts of plug 4 and jack 3, and the winding of a cutoff relay 16 to grounded battery. Relays 15 and 16 become energized, and the 70 latter opens the circuit of relay 13, whereupon lamp 14 is extinguished. A further circuit is closed from the plus pole of battery, through repeating coil winding 17, the tip contacts of plug 4 and jack 3, the calling 75 substation, the ring contacts of jack 3 and plug 4, the winding of a supervisory relay 18, and repeating coil winding 19 to the minus pole of battery. Relay 18 closes a shunt around a supervisory lamp 20. 80

The connecting operator sets now contacts 5, 6, of a selector switch of any well-known design, to extend the calling line through a trunk 7, 8 to another operator's position. After contacts 5, 6 have been set, the connecting operator converses with this latter mentioned operator through a well-known call circuit (not shown). After the second operator has learned the number of the called subscriber, she inserts her plug 9 into jack 90 10 in which the called subscriber's line terminates. A circuit is established thereupon from grounded battery through the winding of the called subscriber's cutoff relay 21, the sleeve contacts of jack 10 and plug 9, and the 95 winding of a relay 22 to ground. This relay closes a circuit from the plus pole of battery through its armature and front contact, contact 23 and the power magnet of a sequence switch 24 to the minus pole of battery. Under the control of a normal spring 25, the sequence switch is moved out of position 1 into position 10. The sequence switch 24 is of the same structure as the one described in Patent 1,127,808. 100

With the exception of a normal or master contact 25 of sequence switch 24, all the sequence switch contacts are closed only in the 105

sequence switch positions indicated adjacent to the respective contacts. The sequence switch contact 25 is closed in all the positions of the sequence switch 24, except in the 5 positions indicated adjacent to this contact. Sequence switch contacts 33 and 49 are closed in all the positions of the sequence switch 24.

When the sequence switch reaches position 4, a circuit is closed from grounded battery, through 26, 27, 28, 7, 5, 29, 30, to ground. Relay 27 closes a circuit: the minus pole of battery, 31, contact of relay 27, 32, 33, 34, 35, plus battery. Relay 34 closes 15 a circuit from grounded battery, through 36, 37, 38 and 39 to ground. In position 5 of the sequence switch, the above traced circuit of relay 27 is replaced by a circuit closed through the left-hand contact of relay 38 and sequence switch contact 40.

In position 10 of the sequence switch, a circuit is closed from the minus pole of battery, through contact 31, the contact of relay 27, sequence switch contacts 32 and 25 41, the windings of relays 42 and 43, and the front contact and armature of relay 22 to the plus pole of battery. Only relay 42 becomes energized, relay 43 being shunted. Relay 42 closes a ringing circuit from 30 ground, through a ringing current generator 44, the winding of a marginal ringing relay 45, the lower front contact and armature of relay 42, the ring contacts of plug 9 and jack 10, the called subscriber's line, the 35 tip contacts of jack 10 and plug 9, and the upper front contact and armature of relay 42 to ground. As soon as the called subscriber removes his receiver from the switchhook, relay 45 becomes energized, and 40 by opening at its back contact the shunt around the winding of relay 43 permits the energization of this relay, which then short-circuits relay 42 and causes thus the cutting off of the ringing current and the deenergization of ringing relay 45.

Upon the completed establishment of the connection, a supervisory relay 46 becomes energized in the well-known manner and closes a circuit from ground, through its 50 front contact and armature, the right armature and front contact of relay 34, repeating coil winding 47, sequence switch contacts 48 and 49, trunk conductor 8, contact 6, the winding of a supervisory relay 50, 55 and the repeating coil winding 51 to grounded battery. Relay 50 closes a shunt around a supervisory lamp 52, contact 53 being closed at this time. The closure of contact 53 may be effected automatically under the 60 control of a sequence switch associated with the selector, the wipers of which are indicated at 5 and 6, or manually under the control of the operator. The sequence switch associated with the selector is separate from 65 the sequence switch 24, and operates for

controlling the operation of the selector switch in a manner similar to the sequence switch 200 shown in Fig. 1 of a patent to A. E. Lundell, No. 1,168,319, patented January 18, 1916.

When both the calling and called subscribers restore their receivers to the switchhook, relay 18 becomes deenergized and opens the shunt around lamp 20, which will light. Relay 46 also becomes deenergized, 70 opening the circuit of relay 50, which releases and permits supervisory lamp 52 to become lighted. The connecting operator opens now both trunk wires by disconnecting contacts 5, 6, whereupon the circuit of relay 27 is opened, and this relay in turn opens the circuit of relays 34 and 43. Relay 34 connects relay 38 at its contact 54, through sequence switch contact 55 to the trunk wire 8. The path for battery current, however, is open at contact 6, so that relay 38 reacts, opening at its left-hand contact the circuit of relay 27, and closing at its right-hand contact through a sequence switch contact 56 a circuit for sequence 85 switch 24. The sequence switch is moved out of position 10 into position 1, in which position a circuit is closed from the minus pole of battery through sequence switch contact 58, a lamp 59, sequence switch contact 61, and the front contact and armature of relay 22 to the plus pole of battery. The operator noticing the steady lighting of lamp 59, removes plug 9 from jack 10, causing thereby the deenergization of relays 21 90 and 22.

Should the operator remove plug 9 from jack 10 prior to the severing of contacts 5 and 6, i. e. while sequence switch 24 is in position 10; upon the deenergization of relay 22, a circuit is closed from the plus pole of battery, through the armature and back contact of this relay, sequence switch contact 62, lamp 59, and an interrupter 63 to the minus pole of battery. Under the control of this interrupter, lamp 59 is caused to flash, indicating to this operator that she has prematurely removed her plug from the jack, and if she remembers the number of the called subscriber, she is thus enabled to 110 reestablish the connection in due time.

If, for any reason, it is desired to rering the called party, the operator may reestablish the active condition of the ringing mechanism by momentarily depressing a 120 ringing key 64. Prior to this, there had existed a closed signaling circuit through the trunk wire 7, as follows: grounded battery, the left-hand contact of relay 38, 40, 27, 28, 7, 5, 29, 30, ground; also a second 125 local circuit: plus battery, 35, 34, 33, 32, the contact of relay 27, 31, minus pole of battery, and a third local circuit: ground, 39, 38, 37, 36, grounded battery. The depression of the ringing key 64 causes re- 130

lay 27 to react, opening at its contact the circuit of relay 43 and the second local circuit. Relay 43 opens the shunt around relay 42 and recloses the shunt about itself. 5 Relay 34 also reacts, opening at its right-hand contact the supervisory signaling circuit, closing at 54 a connection for relay 38 to wire 8 of the trunk, and opening at 37 a contact in the third local circuit. 10 Contact 54 makes before contact 37 breaks, so that relay 38 will remain energized, provided it finds a substitute path for battery current over the trunk wire 8, which it does under the present assumption, the 15 circuit being as follows: ground, 39, 38, 54, 55, 49, 8, 6, 50, 51, grounded battery. As the ringing key is but momentarily depressed, the original signaling circuit over trunk wire 7 is closed again, and relay 27 20 acts to reclose the original local ringing circuit, causing the ringing relay 42 to again apply ringing current to the called line. If and when the subscriber again responds, relays 45, 42 and 43 act as before, cutting off 25 the ringing current. The operation of re-ringing may be repeated as often as required.

What is claimed is:

1. In a telephone exchange system, a plurality of lines, means for extending a calling line toward a called line, a switch for connecting the extended calling line to the called line, a signal associated with said switch, means operative upon the restoration of said means for continuously actuating said signal, and means operative if said switch is restored prior to the restoration of

said means for interruptedly actuating said signal.

2. In a telephone exchange system, a plurality of lines, an automatic selector switch for extending a calling line toward a called line, an operator's plug and jack for connecting the extended calling line to the called line, a disconnect signal associated with said plug, means for continuously actuating said signal if said selector switch is restored and said plug is in use, and means for flashing said signal if said plug is removed while said switch is actuated. 50

3. In a telephone exchange system, a plurality of lines, an automatic selector switch for extending a calling line toward a called line, an operator's plug and jack by means of which the extended calling line may be 55 connected to the called line, a ringing apparatus and a disconnect signal associated with said plug, a two-wire trunk extending between said selector switch and said plug, means operative after the completed establishment of the connection upon the opening of one of the trunk wires for actuating the ringing apparatus a desired number of times, means operative upon the opening of both trunk wires for continuously actuating 60 said disconnect signal, and means operative if said plug is removed prior to the opening of both trunk wires for flashing said disconnect signal. 65

In witness whereof, I hereunto subscribe 70 my name this 13th day of January A. D., 1916.

ALBEN E. LUNDELL.
